CLAIM

The ornamental design for a face display for a timepiece, substantially as shown and described.

DESCRIPTION

FIG. 1 is a front elevational view of the face display for a timepiece showing a typical time indication of 5:45.

FIG. 2 is a front elevational view of a face display for a timepiece shown in a wrist watch case, an environment in which the design is used, and showing a typical time of 5:45; and,

FIG. 3 is a front elevational view of another embodiment of the face display for a timepiece.

The broken lines showing of a watch is for illustrative purposes and is not a part of the claimed design.

The face display for a timepiece is conventionally of no appreciable thickness, and the rear is flat and unornamented.
